UNITED STATES PATENT OFFICE.

EMANUEL F. SHIPMAN, OF PHILADELPHIA, PENNSYLVANIA, ASSIGNOR TO INDUSTRIAL PRODUCTS COMPANY, A CORPORATION OF PENNSYLVANIA.

COLLAPSIBLE TOOL-BAG FOR LINEMEN.

1,374,960.

Specification of Letters Patent. Patented Apr. 19, 1921.

Application filed April 17, 1920. Serial No. 374,525.

To all whom it may concern:

Be it known that I, EMANUEL F. SHIPMAN, a citizen of the United States, residing at Philadelphia, in the county of Philadelphia and State of Pennsylvania, have invented certain new and useful Improvements in Collapsible Tool-Bags for Linemen.

This invention relates to collapsible canvas tool bags for linemen, and one of the primary objects of my invention resides in the provision of an improved tool bag which is of simple and stout construction and which is composed of non-conducting material.

Another object of the invention resides in the provision of an improved tool bag having a supporting means so arranged that when the bag is hung from a pin, step, or the like, the bag will partially collapse, if the bag is abutting the adjacent structure, or if the bag hangs free, it will assume an angular position, in either case rendering the contents of the bag more accessible and facilitating the return of tools after use.

Another object of the invention resides in the provision of an improved bag which, when completed, cannot be turned inside out.

The foregoing, together with such other objects as may hereinafter appear, or are incident to my invention, I obtain by means of a construction which I have illustrated in preferred form in the accompanying drawings, wherein—

Figure 1 is a partial side elevation and section of a tool bag embodying my improvements; Fig. 2 is a side elevation of a detail of my invention; Fig. 3 is a section taken on the line 3—3 of Fig. 2; and Fig. 4 is a section taken through another portion of the bag to illustrate another detail of my improvement.

Referring now to Fig. 1, it will be seen that the bag comprises a bottom 7, preferably composed of wood, or other suitable non-conducting material; the side 8 preferably composed of a single piece of canvas; the handle 9 for carrying the bag; and the loop 10 by means of which the bag is supported.

A hoop 11 is provided at the top of the bag. The bag is made as follows: The longitudi-

dinal edges of the canvas are sewed together forming the canvas into a cylinder which is turned inside out. The bottom 7 is then inserted into an end of the cylinder and a rope 12 is tied around the end of the canvas, forcing the same into the groove 13 formed in the periphery of the bottom 7, the rope being then stapled or otherwise secured in position. The canvas is then turned right side out, the hoop 11 placed therein and the upper end of the bag folded or lapped over for a considerable distance, the lapping portions being stoutly stitched immediately below the hoop 11, as indicated at 14 and also at the bottom of the lapped over portion, as indicated at 15.

At diametrically opposite points metallic eyelets 16 are provided. These eyelets are located over apertures in the canvas wall and are secured in proper position by means of a heavy cord 17 which is spirally wound around the eyelets and secured through the canvas as indicated in Figs. 2 and 3. The eyelets are located just below the stitching 14 and when covered in the manner described they are completely insulated and at the same time securely fastened.

On one side of the bag, I provide a pair of eyelets 18 through which I pass the ends of the rope 10, such ends being knotted in the interior of the bag to prevent the ends from pulling out. The hoop 11 is smaller in diameter than the bottom 7 so that when the hoop is sewed in place, the bag cannot be turned inside out.

When the bag is suspended from the loop 10 in the clear, the bottom of the bag will swing inwardly by the action of gravity, thus causing the mouth of the bag to extend at an angle which facilitates the removal and replacement of the linemen's tools. Similarly, if the bag be supported from a pin on the pole in such manner that the bottom of the bag abuts the pole, then the far side of the bag will partially collapse causing the mouth of the bag to extend in an angular plane.

The bag is made with a diameter such that the bag may be passed through the wires.

It will be seen that when the bag is emptied of tools, it may be collapsed into a small compass.

I claim:—

- 5 A lineman's tool bag comprising a rigid closed bottom, a flexible body portion having an open upper end, a hoop member surrounding the upper end and around which the flexible body portion is lapped, eyelets extending

through the body portion in the lapped zone, 10 insulating material covering said eyelets, a handle engaging said eyelets and an additional suspension device carried by said body, substantially as described.

In testimony whereof, I have hereunto 15 signed my name.

EMANUEL F. SHIPMAN.
